WILLIS B. BLACKWELL AND WILLIS J. BLACKWELL, OF NEW YORK, N. Y.

DISPLAY-SUPPORT.

1,337,816.

Specification of Letters Patent. Patented Apr. 20, 1920.

Application filed February 19, 1919. Serial No. 277,913.

To all whom it may concern:

Be it known that we, WILLIS B. BLACKWELL and WILLIS J. BLACKWELL, both citizens of the United States, and residents of 5 the city of New York, borough of Manhattan, in the county and State of New York, have invented a new and Improved Display-Support, of which the following is a full, clear, and exact description.

10 This invention relates to display devices and has particular reference to simple, cheap, reliable and efficient means for supporting a card, advertisement or other display matter upon an upright temporary 15 support such as a bottle neck, tin can or other container.

Among the objects of our invention is to provide attractive window displays of bottle goods, any one or more of the bottles of 20 the display being employed to support a display card or the like description of the goods, the means for supporting the display being held by the bottles in substantially invisible or inconspicuous position.

25 Another object of the invention is to provide a spring clip of suitable form for self support upon a bottle neck or other upright member, said clip including a plurality of fingers or holders at the back of the bottle 30 neck or support for holding a display card.

With the foregoing and other objects in view the invention consists in the arrangement and combination of parts hereinafter described and claimed, and while the invention 35 is not restricted to the exact details of construction disclosed or suggested herein, still for the purpose of illustrating a practical embodiment thereof reference is had to the accompanying drawings, in which like 40 reference characters designate the same parts in the several views, and in which—

Figure 1 is a front elevation showing one manner of use of our improvement.

Fig. 2 is a perspective view of our improved display support detached.

Referring now more specifically to the drawings we indicate diagrammatically in Fig. 1 an upright member such as a bottle B having a neck 10 adapted to have snapped 50 thereupon the loop portion 11 of a spring clip having terminal fingers 12 preferably spaced laterally from each other with the points of the fingers projected upward at the rear of the bottle neck. We make these display supports 55 preferably of a good quality of steel or other spring wire and so shaped as to

have an inherent tendency to automatically hold in supporting position upon a bottle neck of any ordinary size.

In the practice of the invention as suggested in Fig. 1 a display card C depending upon its size or other conditions may be supported upon one support on a single bottle, or on several supports on as many bottles arranged in a row. Taking into consideration 60 the fact that bottled goods are commonly put on the market nowadays with metal caps it is inconvenient, if not impossible, for cards or the like to be supported directly on their tops without some special appliance, 65 but even in connection with bottles having cork stoppers to employ pins or the like sticking into the cork stoppers to hold the display cards is both inconvenient and productive of an unsightly display. As will be 70 appreciated from the drawings a display support such as we have shown may be snapped or clamped upon a bottle neck and be practically invisible from the front the only portion being visible being the loop 11, 75 which in many instances is practically invisible because it is parallel to the top or cap of the bottle. The fingers 12 being back of the bottle neck and cap are invisible whether a display card be supported thereon 80 or not. In supporting the card, however, the lower edge of the card rests directly upon the device, and the back surface of the card rests against the points of the fingers. Rearward tilting of the card is limited by 90 said finger points and contact between the lower edge of the card and the device. Obviously for supporting a large display card two or more bottles in a row are preferably used, the card extending between them so as 95 to be supported upon several of the clips on the same level.

The form shown has in addition to the loop 11 and fingers 12 having upwardly directed points, a double fold or bend 13^a and 100 13^b between each finger and the loop. This arrangement provides two additional fingers or members 12^a and 12^b. Obviously a display card or the like may be supported directly upon the loops 13^a and 105 13^b and lean rearward against the finger points 12, or if the clip is applied to the bottle neck in inverted position the same display card might be supported upon the bends 13^b and lean rearward against the 110 then upper ends of the members 12^a. We prefer, however, to so bend the holding fea-

tures or portions of the clip as to grip the display card between the fingers 12 and the parts 12^a or between the parts 12^a and 12^b, and in making up certain displays we frequently attach display cards or the like by means of a clip so as to utilize both sets of gripping devices. For example one card may be supported between the fingers 12 and parts 12^a in the position of Fig. 3 while another card or ticket may be slipped upward between the parts 12^a and 12^b so that the two displays will be held independent of each other.

In the foregoing principal forms of our invention it will be noted that the device comprises an open spring loop terminating in spaced upward and substantially parallel fingers movable laterally toward and from each other in accordance with the diameter

of the container around which the loop portion is embraced. Said loop portion at all points remote from the finger portion of the device lies in a continuous smooth curve in a plane essentially perpendicular to the plane of the terminal fingers. 20
25

We claim:

The herein described display support comprising an open loop of spring wire having terminal gripping ends, the extreme ends constituting straight parallel fingers, while the portions of the wire adjacent to the fingers are bent into double folds or bends which coöperating with the fingers constitute frictional grips for the device to be displayed. 30
